UNITED STATES PATENT OFFICE.

LEWIS C. MYERS, OF FREEPORT, NEW YORK, ASSIGNOR TO ROYAL TYPEWRITER COMPANY, INC., OF NEW YORK, N. Y., A CORPORATION OF NEW YORK.

TYPEWRITING MACHINE.

Application filed December 23, 1922. Serial No. 608,722.

To all whom it may concern:

Be it known that I, LEWIS C. MYERS, a citizen of the United States, residing in Freeport, in the county of Nassau and State of New York, have invented certain new and useful Improvements in Typewriting Machines, of which the following is a specification.

This invention relates to typewriting machines in which provision is made for regulating the margins of the printed matter. In such machines stops are adjustably mounted on a transverse margin stop rail secured to the carriage and movable back and forth therewith, and a centrally located stop lever is adapted to be engaged by the margin stops to limit the movement of the carriage in both directions. In order that the printed matter may be at will widened, the carriage stop lever is connected to a key known as the margin release key by operating which the carriage may be released and moved to a further extent in either direction to a limited extent. Such machines are also generally equipped with a tabular rail carrying adjustable stops which are adapted at times to engage the centrally located stop lever, the mechanism being so organized that when desired the central stop lever may be so moved as to clear the usual margin stops on the margin stop rail when the carriage is moved back and forth, but which limits the movement of the carriage to the desired extent according to the location of the tabular stops. Ordinarily a machine of this class is provided with two adjustable margin stops but often it is necessary to print matter having a definite or uniform margin and also narrower matter and this involves either a separate adjustment of the end stops or the use of an intermediate stop.

According to my invention I equip a typewriting machine with a single central stop lever, two adjustable margin stops as usual and an adjustable intermediate stop, and I also employ a tabular rail equipped with adjustable stops. Means is provided whereby the central stop lever may be so held as to allow the carriage to move to the full extent limited by the end margin stops or to move from either end stop to the intermediate stop and means is also provided whereby the central stop lever may be so

set that it will clear all of the margin stops, but will be engaged by the tabular stops. The mechanism is so constructed that the central stop lever may be so locked as to hold it in the position to which it is set and to at will release it from such position when desired.

In the accompanying drawings:—

Figure 1 is a sectional view of portions of a typewriting machine of the Royal standard type showing my improvements applied thereto.

Figure 2 is a detail view of the locking devices for the central stop lever of the margin control devices.

Figure 3 is an end view of the devices for controlling the margin stop mechanism.

Figure 4 shows the devices illustrated in Figure 3 in a different position.

Figure 5 is a plan view of portions of the carriage showing the relation of the central stop lever with the margin stop rail and the tabular rail.

The illustration is diagrammatic so far as the positions of the central stop lever is concerned.

Figure 6 illustrates diagrammatically how certain kinds of printing is controlled by the mechanism.

Figure 7 is a view of the keys or buttons controlling the margin release and the margin release lock mechanism.

Figure 8 is an elevation showing the connections between the central stop lever and the devices by which it is operated.

In Figure 1 I have shown only so much of a typewriting machine of the Royal type as is necessary to indicate how my improvements are applied thereto. Parts of the main frame are indicated at A. B indicates the carriage and C the platen. The carriage is equipped with a margin stop rail D and a tabular rail E of the usual kind and mounted in the usual way. The tabular rail carries adjustable stops e and the margin stop rail carries adjustable margin stops F and G of any suitable kind and applied in the usual way. The margin rail is also equipped with an intermediate stop H similar in construction to the stops F and G but having its rear portion set closer to the margin rail than the stops F and G.

The central stop lever K is pivoted between its upper and lower ends at l to a

2 bracket L secured to the rear portion of the frame A. The upper portion of the lever is properly formed and located to engage the margin stops and the tabular stops and its 5 lower portion is connected by a link M with the upper end of a vertical lever N pivoted at n to the frame bar O. A spring P carried by the bracket L bears against the lever K above its pivot and tends to hold the upper 10 end of said lever in position to engage the end stops F and G and the intermediate stop H. Said spring P yields to permit the upper end of the lever to be set to clear the intermediate stop and to engage the stops 15 F and G or to clear not only the intermediate stop but also the stops F and G and to only engage the tabular stop. The lever N is connected by a link Q to a bell crank lever R pivoted to a frame S and the upper 20 end of this lever is engaged by a push rod T mounted to slide and to turn in the support S. The push rod T carries intermediate its front and rear ends a laterally projecting pin t and the front end of the rod 25 is secured to a cross piece V carrying at opposite ends buttons v, v', one of which is marked "Margin release" and the other "Margin release lock". The pin t of the push rod extends through an angular slot w 30 in a plate W secured to the support S and is adapted to move fore and aft and sidewise in said slot. When the push rod T is in the position shown in Figure 1 which is the normal position for a wide margin or usual 35 typewriter width, the stop lever K is in the position shown in Figure 1 and will clear the intermediate stop H and the tabular stops so that the carriage may move sidewise to the full extent limited only by the stops 40 F and G. It will be observed that the spring P presses the upper portion of the lever K forwardly to the extent limited by the rod T.

When the push rod T is in the position 45 shown in Figure 8 the spring P will move the upper portion of the lever K forwardly to a greater extent into the path of the margin stop H so that the carriage can only travel between the stops F and H. There- 50 fore, by manipulating the buttons v, v', the stop lever K can be set for the kind of work desired. When the push rod T is moved forward in the manner indicated in Figure 1, it may be locked in this position by turn- 55 ing the rod until the pin t engages an offset part of the slot w. When the push rod is in the position shown in Figure 8 the pin t rests against the front end of the slot w. The rod may be unlocked from its position 60 shown in Figure 1 by turning the rod in the manner indicated and when thus re- leased the central stop will be moved back to the position shown in Figure 8 to engage the intermediate margin stop H.

65 In order to make provision for tabular work I employ a key lever X pivoted at n to the frame bar O and having an upwardly extending rear portion x having a flange x' which engages behind the lever N. The upward movement of the lever X is limited by a stop x² and this lever is normally drawn upwards by a spring x³. When the key lever X is depressed it moves the lever N forwardly against a stop Z and this forward movement of the lever N causes the upper portion of the central stop lever K to be moved to the position shown at z² in Fig. 5 to engage a tabular stop e. It will, therefore, be seen that when the lever X is depressed it moves the lever K to a greater extent rearwardly than when moved by buttons v, or v'. Inasmuch as it is desirable in such machines to employ what is known as a palm tabular key I may connect such a key with the lever N in the manner shown in Figure 1. This palm tabular key K' is pivotally mounted at k in the machine frame and has an upwardly and rearwardly extending arm k' which is connected by a link k² to an arm n' extending rearwardly and downwardly from the lever N. It is normally held in raised position by a spring k³. By depressing either the key X or the key K' the stop lever K may be moved to a position to engage the tabular stops.

In Figure 5 I have shown diagrammatically the relation of the center stop lever, or "center stop" as it is usually called, with the margin stops and the tabular stops. When the center stop is in the position indicated at z it will be engaged by the right hand margin stop F and intermediate stop H, and a transverse movement of the carriage will be thus limited and a wide left hand margin obtained. When the center stop is in the position z² the movement of the carriage will be limited by the two end margin stops F and G and when the center stop is at z² none of the stops F, G, and H will be engaged by the center stop but said center stop is engaged by the tabular stops. In this way as the center stop is moved to the different positions, several different kinds of work can be produced.

The means shown for operating the center stop is of the simplest character and operates most efficiently. It will be observed that the center stop lever is operated and set by a single link connection with the single vertical lever N and that the movement of this lever is controlled by the push rod T and by either of the tabular keys.

When the stops are set to produce work with the wide margin as indicated in Figure 6 at the left of the word "about" and it is desired to produce printed matter with a wide margin the center stop can be easily shifted from this position by means of the buttons v, v' and in like manner the center stop can be shifted by the same devices to

change from a narrow margin to a wider one. This characteristic of the mechanism is especially useful in printing insurance policies and the like.

5 It is also apparent that after printing with a narrow margin the carriage may be quickly shifted to a position to print with a wide margin. For instance, referring to Figure 6, if after printing wide line XY-Z
 10 it is desired to print the word "about" (or any other word) to commence a paragraph with a wide margin, the depression of either tabular key will permit the carriage to be quickly shifted or jumped to the proper position and when the tabular key is released and the buttons *v*, *v'* properly set, the center stop may be positioned to do the desired work. In some cases the carriage is returned to the full length of its travel. In such
 15 cases the tabular key may be depressed and the carriage will jump to the position determined by the tabular stop, for instance, to the position 40 indicated in Figure 5. The work may then proceed and as other lines
 20 are written, the carriage when next returned will be arrested at the tabular stop instead of traveling its full range of movement, or a movement limited by the margin stops. When it is desired to change the character
 25 of the work, the margin release key *v* may be actuated to release the margin release lock and the center stop may be shifted to the position shown in Figure 8 to operate between the margin stops F and H. In this
 30 way a great variety of printed matter may be produced.

I claim as my invention:

1. In a typewriting machine, a carriage provided with a margin stop rail and a tabular stop rail, end margin stops and an intermediate stop on said margin stop rail, one or more stops on the tabular rail, a center stop adapted to engage any of said stops, a vertically arranged lever operatively connected with the center stop, means under the control of the operator and connected with said vertical lever for setting the center stop in three positions to engage the margin stops, the intermediate stop, or the tabular stops, and devices for locking said setting means to hold the center stop in one position to which it is set.

2. In a typewriting machine, a carriage provided with a margin stop rail and a tabular stop rail, end margin stops and an intermediate stop on said margin stop rail, one or more stops on the tabular rail, a center stop adapted to engage any of said before mentioned stops, a vertically arranged lever operatively connected with the center stop, a bell crank lever connected with said vertical lever, and means for limiting the movement of said bell crank lever to determine the limits of movement of the center stop.

3. In a typewriting machine, a carriage

provided with a margin stop rail and a tabular stop rail, end margin stops and an intermediate stop mounted on said margin stop rail, one or more stops mounted on the tabular rail, a center stop adapted to engage any of said before mentioned stops, a vertically arranged lever operatively connected with the center stop, means under the control of the operator and connected with said vertical lever for setting the said center stop in the required position to engage any of the stops on the margin stop rail, and a lever operating upon said vertical lever to move the center stop to a position to clear the stops on the margin stop rail and to engage the stops on the tabular rail.

4. In a typewriting machine, a carriage, margin and tabulating stops, a single element adapted to cooperate with any of said stops to position said carriage, and means whereby said element may be operated by a margin release key, a tabular key, or a palm tabular key.

5. In a typewriting machine, a carriage, margin and tabulating stops, a single element adapted to cooperate with any of said stops to position the carriage, and means whereby the element may be moved to two cooperative positions by a margin release key and to a third cooperative position by either a tabular or a palm tabular key.

6. In a typewriting machine, a carriage, margin, tabulating and intermediate margin stops, a cooperating stop, a single element adapted to move the cooperating stop to three different positions to cooperate with the three types of stops, and means whereby said element may be independently operated by three different instrumentalities.

7. In a typewriting machine, a carriage, margin and tabulating stops carried thereby, a cooperative stop, and a single pivotal member connected therewith and independently operated by a margin release key to two positions, and by a tabular key or a palm tabular key to a third position.

8. In a typewriting machine, a carriage, right and left hand margin stops, an intermediate margin stop and tabulating stops carried thereby, a cooperating stop, a single element connected thereto, a combined margin release and margin release lock key for moving said element to cause the cooperating stop to engage either the right and left hand margin stops, or one of said stops and the intermediate stop, and a tabular key for moving said element to cause the cooperating stop to clear all of the margin stops and engage the tabulating stops.

9. In a typewriting machine, a carriage, right and left hand margin stops, an intermediate margin stop and tabulating stops carried thereby, a cooperating stop, a single element connected thereto, a combined margin release and margin release lock key for

1 moving said element to cause the cooperating stop to engage either the right and left hand margin stops, or one of said stops and the intermediate stop, and a tabular key and a palm tabular key each connected to move said element to cause the cooperating stop to clear all of the margin stops and engage the tabulating stops.

10. In a typewriting machine, a carriage, 19 a plurality of stops carried thereby, a co-operating stop, a single intermediate device connected to said cooperating stop, and means for moving said intermediate device to different positions for determining right 15 and left hand and intermediate margins or column tabulating.

11. In a typewriting machine, a carriage, 29 a plurality of stops carried thereby, a co-operating stop, a single intermediate device connected to said cooperating stop, and a combined margin release and margin release lock key, a tabular key and palm tabular key, all connected to move said intermediate device to different positions for determining

right and left hand and intermediate margins or column tabulating. 25

12. In a typewriting machine, a carriage, end and intermediate margin stops, tabular stops, a cooperating stop block adapted to be positioned to engage any of said stops, 30 means operated by either a margin or tabular key for respectively effecting engagement and disengagement of the stop block with the corresponding stops, and means for locking the stop block out of the path of 35 the intermediate margin stop and the tabular stops.

13. In a typewriting machine, a carriage, end and intermediate margin stops, tabular stops, a cooperating stop block adapted to 40 be positioned to engage any of said stops, and means operated by either a margin key, a tabular key, or a palm tabular key for effecting engagement and disengagement of the stop block with the other stops. 45

In testimony whereof, I have hereunto subscribed my name.

LEWIS C. MYERS.
